UNITED STATES PATENT OFFICE.

MIZUHIKO NAKAYAMA, OF TOYOTAMAGUN TOKYO-FU, AND KEIJIRO ADACHI, OF SHITAYA-KU, TOKYO, JAPAN.

PROCESS OF UTILIZATION OF WASTE OR SCRAPS OF LEATHER.

1,400,899.

Specification of Letters Patent. Patented Dec. 20, 1921.

Application filed December 18, 1919. Serial No. 345,859.

To all whom it may concern:

Be it known that we, MIZUHIKO NAKAYAMA and KEIJIRO ADACHI, citizens of the Empire of Japan, residing at No. 892, Tozuka-machi, Toyotamagun, Tokyo-fu, and No. 2 Nishikuromon-cho, Shitaya-ku, Tokyo city, Japan, have invented certain new and useful Improvements in Processes of Utilization of Waste or Scraps of Leather; and we do hereby declare the following to be a full, clear, and exact description of the invention, such as will enable others skilled in the art to which it appertains to make and use the same.

The present invention relates to a process of utilization of waste or scraps of leather, and has for its objects to get a durable material of fine exterior view, at a cheap cost out of such waste or scraps, to be used in manufacturing the trunks or the like.

In the accompanying drawings:—

Figure 1 is a plan view of a board or cloth, upon which cut pieces of leather are arranged according to the invention, and Fig. 2 is a magnified sectional view of the above.

According to the present invention, waste or scraps of leather is first cut into pieces (1) (1) of such shapes as can be arranged or connected together allowing no space or gap among the joints of the pieces, whereby an optional pattern being had: 2nd, the cut pieces are pasted on a board or cloth (2) (2), making the surface of the pieces uniform: 3rd, the joints (3) (3) of the cut pieces are sewed together in a suitable way: 4th, pressure is given on the sewed parts to such extent that the seams are pressed down to make hollows (4) (4): 5th, a solution

of gum or celluloid of great density (5) is 40 coated on the seams or the hollowed place.

Thus treated, the pieces of leather which were sewed together have a very fine exterior view, an optional pattern being had, and are most suited for manufacturing trunks 45 or the like, duly guarded from agnail caused by frictions, the seams are being pressed to hollow, and the agnail being more effectually prevented as a result of the said solution being coated on the surface of the seams. 50

Having thus described the nature of our invention, what we claim is:—

1. A process of utilization of waste or scraps of leather by cutting such waste or scraps into pieces of such shapes as can be 55 arranged or connected together allowing no space or gap among the joints of the pieces, whereby an optional pattern being had, pasting the cut pieces on board or cloth or the like sewing the joints of the pieces together, 60 and then coating the surfaces of the seams with thread protecting material.

2. A process of utilization of waste or scraps of leather by cutting such waste or scraps into pieces of such shapes as can be 65 arranged or connected together allowing no space or gap among the joints of the pieces, whereby an optional pattern being had, pasting the cut pieces on board or cloth or the like, sewing the joints of the pieces together, 70 pressing down the seams to hollow, and then coating a solution of gum or celluloid of great density on the surface of the seams.

In testimony whereof we affix our signatures.

MIZUHIKO, NAKAYAMA.
KEIJIRO, ADACHI.
